The ornamental design for a combination bib and handled feeding bottle, as shown.

DESCRIPTION

FIG. 1 is a front elevational view of a combination bib and handled feeding bottle showing my new design in use, the broken lines partially showing a child being for illustrative purposes only and forming no part of the claimed design;

FIG. 2 is a right side elevational view thereof shown flattened, and the left side being a substantial mirror image; and,

FIG. 3 is a front elevational view thereof shown flattened, the bottle being removed, and the rear being plain and unornamented.

The bottom of the bottle holder is circular and allows the bottom of the feeding bottle to be visible.
